UNITED STATES PATENT OFFICE

112,043

DESIGN FOR A WATER JUG OR SIMILAR ARTICLE

Rowena Reed Kostellow, Pittsburgh, Pa., assignor to United States Glass Company, Pittsburgh,
Pa., a corporation of Pennsylvania

Application February 5, 1938, Serial No. 74,895

Term of patent 3½ years

To all whom it may concern:

Be it known that I, Rowena Reed Kostellow, a citizen of the United States, residing at Pittsburgh, county of Allegheny, in the State of Pennsylvania, have invented a new, original, and ornamental Design for a Water Jug or Similar Article, of which the following is a specification, reference being had to the accompanying drawing, forming a part thereof, in which—

Figure 1 is a side view in elevation of a water jug or similar article showing my new design; and

I claim:

The ornamental design for a water jug or similar article, substantially as shown and described.

ROWENA REED KOSTELLOW.
